(Cl. D34—5)

To all whom it may concern:

Be it known that we, George T. Kruithof and John W. K. Jurrat, both citizens of the United States of America, and both residents of the city of Glendale, in the county of Los Angeles and the State of California, have invented a new, original, and ornamental Design for a Shuffle Board Game Device, of which the following is a specification, reference being had to the accompanying drawings, forming a part of this invention.

In the drawings:

Figure 1 is a side perspective view of a shuffle board game device, showing my new design, and

Figure 2 is a perspective view of a portion thereof showing a part in closed position.

We claim:

The ornamental design for a shuffle board game device, substantially as shown.

GEORGE T. KRUITHOF.
JOHN W. K. JURRAT.
